UNITED STATES PATENT OFFICE.

ZACHARIAH A. TAYLOR, OF RIVERSIDE, CALIFORNIA.

WASHER.

1,329,441.

Specification of Letters Patent.

Patented Feb. 3, 1920.

Application filed November 29, 1918. Serial No. 264,618.

To all whom it may concern:

Be it known that I, ZACHARIAH A. TAYLOR, a citizen of the United States, residing at Riverside, in the county of Riverside and 5 State of California, have invented a new and useful Washer, of which the following is a specification.

The device forming the subject matter of this application is a washing machine, and 10 the invention aims to provide novel means whereby the clothes in the tub may be subjected simultaneously to the action of a ram or pounder, and to air under pressure, the ram and the air supplying means being operated from a single point of force-application.

It is within the province of the disclosure to improve generally and to enhance the utility of devices of that type to which the 20 present invention appertains.

With the above and other objects in view, which will appear as the description proceeds, the invention resides in the combination and arrangement of parts and in the 25 details of construction hereinafter described and claimed, it being understood that, within the scope of what is claimed, changes in the precise embodiment of the invention shown can be made without departing from 30 the spirit of the invention.

In the accompanying drawings:

Figure 1 shows in side elevation, a device constructed in accordance with the invention, parts being broken away, and parts being shown in section; Fig. 2 is a section on the line 2—2 of Fig. 1; Fig. 3 is a section taken through the pump and attendant parts; Fig. 4 is a sectional detail illustrating the upper end of the ram; and Fig. 5 is a 40 section taken on the line 5—5 of Fig. 3.

In carrying out the invention there is provided a base, denoted generally by the numeral 1, the base including a bar 2 having an opening 3 in one end, wherein is received, 45 the lower end of a standard 4, the standard being pivoted to the bar by means of a bolt 5 and being mounted to swing in the opening 3. The numeral 6 designates, generally, a lever, preferably including parallel rods 7 50 united by means of a pivot element 8 with the upper end of a standard 4. The upper end of a post 9 is disposed between the rods 7 and is secured thereto as shown at 10, the post being sustained from the rods 7 by 55 means of a brace 11. The lower end 12 of the post 9 rests on the bar 2 adjacent to one

end thereof. The post 9 carries an outstanding handle 14. At its ends, the bar 2 is provided with slots 15 wherein hook bolts 16 or like attaching elements are mounted, the 60 hook bolts 16 being adapted to coöperate with the head on a tub 17. Obviously, the hook bolts 16 constitute a means whereby the base 1 and the lever 6 may be assembled with the tub 17, and, since the hook bolts 16 can be 65 adjusted inwardly and outwardly in the slots 15, the structure may be held on tubs of different diameters.

A ram, denoted generally by the numeral 18, operates in the tub 17 and includes a 70 foot 19, and a stem 20 secured to the foot as shown at 21. The foot 19 is provided with slots 100 into which socks and other unusually dirty garments may be drawn and held. The stem 20 of the ram passes through 75 a tube 22 journaled in a block 23 located between the rods 7 of the lever 6, the block being mounted to swing on a pivot element 58 carried by the rods. Nuts 24 are mounted on the tube 22 on both sides of the block 80 23. The nuts 24 are not clamped down on the block 23, the construction being such that when the lever is swung upwardly and downwardly on its fulcrum 8—5 the ram 18 will be raised and lowered, it being possible, 85 nevertheless, to rotate the ram, through the instrumentality of a handle 25 secured to the stem 20 of the ram. The handle 25, which is a composite structure, includes a T-coupling 26 through which the stem 20 passes, 90 one arm of the coupling being threaded on the rotatable tube 22. One arm of the T-coupling 26 is closed by means of a plug 27 and into the opposite arm of the T-coupling, a reducer 29 is threaded, a grip 28 being 95 threaded into the reducer, the stem 20 being bound between the inner ends of the plug 27 and the grip. In the outer end of the grip 28, a hole 30 is fashioned. Through this hole, a wire nail or other object may be 100 inserted, for the purpose of rotating the grip, to cause the inner end of the grip to bind against the stem 20 of the ram 18, as shown in Fig. 4. When the grip 25 is rotated, so that its inner end no longer binds 105 on the stem 20, the ram 18 may be adjusted vertically, to regulate the space between the foot 19 of the ram and the bottom of the tub 17.

The invention comprises a pump cylinder 110 31. One end of the cylinder 31 is engaged by the bar 2, and the other end of the cylin-

der is engaged by a head block 32. The head block 32 and the bar 2 preferably are made of wood, and when these elements are drawn against the ends of the pump cylinder by bolts 33, the ends of the cylinder will be closed. There is a passage 34 in the bar 2, which communicates with the lower end of the cylinder 31. A nipple 43 is inserted into the passage 34 and is connected with a flexible tube 35 communicating with a rigid pipe 36 having a horizontal arm 37 located adjacent to the bottom of the tub 17. The pipe 36 is received in any selected pair of seats 38 formed in one edge of the bar 2 and in a strip 39 connected to the bar 2 by the bolt 5 and by an additional bolt 40. The construction is such that the pipe 36 may be moved inwardly and outwardly, depending on the diameter of the tub 17, and it is possible to rotate the pipe 36 if one loosens the bolts 5 and 40, so that the inner end of the arm 37 may be located in different positions with respect to the center of the tub 17. There is a passage 41 in the head block 32, communicating with the upper end of the cylinder 31. A nipple 44 is mounted in the passage 41 and communicates with a flexible tube 42, which, in its turn, communicates with a rigid pipe 45, like the pipe 36, the pipe 45 having a horizontal arm 46. The pipe is engaged, in the manner hereinbefore set forth, with seats 47 formed in a strip 48 and in one edge of the bar 2, the strip being clamped on the pipe 45 by means of bolts 49 passing through the bar 2, the outer one of these bolts 49 serving as a reinforcement for the bar, as does the bolt 5.

The head block 32 has an air inlet 50 communicating with the upper end of the pump cylinder 31 and controlled by a flap valve 51 carried by the head block. The bar 2 has an air inlet 52 controlled by a flap valve 53 attached to the said bar. A piston 54 reciprocates in the pump cylinder 31 and includes a head 55. The piston comprises a stem 56 passing through the block 23 and held thereto by nuts 57, the stem 56 of the piston and the stem 20 of the ram being disposed on opposite sides of the pivot element 58 which supports the block.

In practical operation, when the lever 6 is swung vertically on its fulcrum 5-8, the piston 54 will reciprocate in the pump cylinder 31. Air is admitted into the upper end of the pump cylinder 31 by way of the inlet 50, and air is admitted into the lower end of the pump cylinder by way of the inlet 52. On the down stroke, air is forced outwardly through the flexible tube 35 into the pipe 36 and is discharged through the arm 37 beneath or into the clothes in the tub 17. On the up stroke, air is forced out-

wardly through the flexible tube 42 into the pipe 45, and out of the pipe through its arm 46. As hereinbefore described, the pipes 36 and 45 may be rotated, so as to dispose the inner ends of the arms 37 and 46 in different positions with respect to the center of the tub. Further, the pipes 36 and 45, and consequently, the arms 37 and 46 may be raised and lowered, the clamp strips 39 and 48 permitting such an adjustment. The hook bolts 16 may be moved inwardly and outwardly in the slots 15, thus adapting the structure to tubs of different sizes. The pipes 36 and 45 may also be moved inwardly and outwardly, depending on the diameter of the tub.

When the lever 6 is swung upwardly and downwardly on its fulcrum 5-8, the ram 18 will move with the lever, thus effecting a pounding of the clothes in the tub 15. The ram may be rotated by means of the handle 25, so that the foot 19 of the ram will reach all of the clothes in the tub, and during this operation, the tube 22 rotates in the block 23. By loosening the grip 25, the ram 18 may be raised and lowered, thus to regulate the distance between the foot 19 of the ram and the clothes in the tub. The opening 3 is large enough so that the standard 4 may swing to some extent on the bolt 5, and the stems 20 and 56 are carried by the block or tilttable member 23, which is fulcrumed intermediate its ends on the parts 7 of the lever 6, by means of the pivot element 58. Thus, the stem 20 of the ram and the stem 56 of the pump will be permitted to have vertical right-line reciprocation without appreciable side strain.

Having thus described the invention, what is claimed is:

A washing machine comprising a base; means for securing the base to the upper edge of a tub; a lever fulcrumed on the base; a member pivotally mounted intermediate its ends on the lever; a ram journaled in one end of said member and movable vertically with the lever; a laterally projecting handle secured to the ram above the lever and constituting means for rotating the ram in said member; a double acting air pump comprising co-operating parts, one of which is attached to the other end of said member, the other of which is carried by the base; and conduits leading from the pump and discharging beneath the ram at spaced points.

In testimony that I claim the foregoing as my own, I have hereto affixed my signature in the presence of two witnesses.

ZACHARIAH A. TAYLOR.
